REGISTERING MECHANISM

Edwin Klahn, New York, N. Y., assignor to
Adolph C. Blechner, New York, N. Y.

Application November 21, 1938, Serial No. 241,567

4 Claims. (Cl. 194—74)

The present invention relates to a registering mechanism and particularly relates to such a mechanism as may be utilized as a calendar or associated with a small bank.

Further, it has not been possible without undue complication and expense to provide a registering device which would be tamper-proof and at the same time would operate satisfactorily and accurately over long periods of time and which could be readily reset by the institution when the bank was returned and which at the same time will be capable of recording the accurate number of days per month as contrasted to the usual devices which record the same number of days for every month.

It is among the objects of the present invention to provide an improved registering device of the character above described which may be of gearless construction, will accurately register the number of days of each month and may be distributed without too great cost and which would be durable and which would withstand handling even though considerably handled over long periods of time before return to the institution to be opened.

Another object is to provide an improved automatic or registering device of the character above described which would have a relatively simple recording mechanism which could not be readily tampered with and which, at the same time, could be readily opened and reset to zero position when returned to the banking institution.

Other objects will be obvious or will appear during the course of the following specification.

In accomplishing the above objects, it has been found most satisfactory, according to one embodiment of the present invention to provide a readily detachable casing which casing may be provided with a lever or with a coin actuated device. In the latter case it is provided with slots to receive a coin and to discharge said coin in turn into the interior of the bank.

Preferably, an arrangement is provided by means of which a coin will be carried by a reciprocating plate or carrier which plate or carrier may be actuated from the exterior of the bank to carry the coin from inserted position to discharge position.

At the same time, another plate may be provided actuated by the movement of the coin to operate a ratchet which ratchet may be provided with a cylinder operating or controlling a registering belt.

This belt, or strip, as the case may be, might be caused to pass a window through which an external reading may be had.

The ratchet mentioned is preferably provided with a detent which might be conveniently disengaged together with the pawl when the strip is to be reset by the banking institution without dismantling the registering mechanism.

In a preferred form of the present invention there are provided two cylinders, one of which carries the ratchet over which a continuous strip of paper or cloth passes, said cloth or paper carrying suitable indicia.

At the same time, the casing is provided with an opening over which this strip is passed so that an external reading may be had.

The above and other objects will appear clearly from the following detailed description when taken in connection with the accompanying drawings, will illustrate a preferred embodiment of the inventive idea.

Figure 1 is a front elevational view of the registering mechanism with a portion of the casing broken away to show the interior construction;

25 Fig. 2 is a cross sectional view upon the line 2—2 of Figure 1;

Figure 3 is a side sectional view upon the line 3—3 of Figure 2;

Figure 4 is a fragmentary transverse sectional view upon the line 4—4 of Figure 3;

Figure 5 is a side sectional view upon the line 5—5 of Figure 2;

Figures 6 and 7 are side sectional views similar to Figure 3 showing other positions of the plates;

Figure 8 is a transverse sectional view upon the line 8—8 of Figure 7;

Figure 9 is a transverse sectional view upon the line 9—9 of Figure 2; and

40 Figure 10 is a front elevational view illustrating the location of the coin receiving device of the present invention in a bank device to be distributed by an institution.

Figure 10a is a side view of the upper portion of the tank of Figure 10.

Figure 10b is a plan view of the key upon enlarged scale as compared to Figures 10 and 10a.

Referring to Figure 10, the bank A, has a base 10, a casing 11 and receives the registering mechanism C having the slot or window 12 through which a reading may be had.

The registering mechanism C is provided with a casing E, a pivotally mounted coin throw over plate F, a ratchet actuating or pawl plate G, upper and lower cylinders H and I, the lower car-

ryng a ratchet, a detent element or plate J, and a resetting element K.

Referring first to the casing E, the top wall 13 of the casing is provided with a coin-receiving slot 14, and the side wall 15 is provided with a coin-ejecting slot 16.

The coin enters through the slot 14 and is discharged into the casing 11 through the slot 16.

The coin throw over plate F is pivotally mounted by the screw 17 upon the wall 18 and it fits closely against the wall 18.

The plate F has the inwardly turned elements 19, 20 and the outwardly extending element 21, all of which are struck off from the body thereof. The element 21 serves as a handle and projects through the slot 22a in the wall 18 to enable reciprocation of the plate F. The flanges 19 and 20 project inwardly to receive a coin M, as indicated best in Figure 5.

The plate also has an inturned portion 22 struck off from the body thereof which cooperates with the upper turned over portion 23 of the leaf spring 24. The leaf spring 24 is riveted at 25 to the base plate 26.

The spring 24 normally presses the plate F in the direction indicated by the arrow 27 so that the turned up lug 19 will contact the wall 28 of the casing E.

The vertical reciprocating plate G is provided at its edges with inturned portions 29 (see Figure 4), which rest against the inturned lugs 30 from the side walls 28 and 15. This leaves sufficient space between the plates F and G, indicated by the arrows 31 to receive the coin which is inserted through the slot 14.

The side edges of the plate G ride against the walls 15 and 28 and are held in position thereby and the guide strips 32 (see Figure 4) hold the plate G closely against said turned in lugs 30.

The lower portion of the plate G is provided with an elongated slot 33 which receives the coil spring 34. The plate G is provided with a lug 35 to which the upper end 36 of the coil spring is connected. The lower end of the spring 34 is connected to the base or floor 26 of the casing E.

To the side of the plate G is attached a strip 37, preferably of thin spring steel which has an inturned lug 38 at its upper end (see Figure 2) and has an upturned resilient tongue 39 which cooperates with the ratchet 40 at the end of the cylinder I.

The lower end 40a of the strip 37 projects through the opening 41 in the base plate 26 of the casing E.

From the wall 18 of the casing E is inturned the coin directing lug 42 which directs the coin M upwardly and out through the slot 16 when the lever F is thrown in the direction 43 by the handle member 21.

At the same time, the plate G is provided with an inturned or turned down coin engaging lug 44 against which the coin presses when injected by the lever F resulting in elevation of the plate G and in advance of the ratchet 40 by the spring member 39 by one tooth.

As soon as the coin is passed out through the slot 16, the spring 34 will normally pull said plate G downwardly.

The cylinders H and I are provided with the central drums 45 and 46 which receive the registering strip N and they have the side flanges 47 and 48 which hold the strip N in position.

On the lower cylinder I, one of the side flanges takes the form of the ratchet 40.

Part of the wall 50, as indicated in Figure 2, 75

is pressed out, as indicated at 51 to form a opening to receive the strip N.

On the back of pressed out portion 51 the spring member 53 is carried by the rivet 52, which has the inturned lips 54 to hold the registering strip tautly in position as it passes across the window in being rolled from the cylinder H onto the cylinder I.

Each of the cylinders is provided with the shouldered end portions 55, 56, 57. The terminal portions 57 act as trunnions and fit into openings 58 in the side walls 15 and 28 of the casing E.

The detent plate J has an opening 59 which is received on the shoulder 56 of the cylinder H and it also has the downwardly dependent detent element 60 engaging the teeth of the ratchet 40. The outwardly extending portion 61a is designed to cooperate with the lug 38 of the strip 37 carried by the plate G.

The leaf spring 62 is riveted to the wall 50 at 61 and it has a portion 63 which tends to press against the portion 64 of the detent element J tending to move it in the direction indicated by the arrow 65 in Figure 2.

The plate G, at its lower edge, has the in-turned flange 66, which normally rests upon the peak 67 of the upturned portion 68 on the plate K.

The plate K has a pivotal connection 69 to the base 26 and it also has a down turned lug portion 70 which rides in the slot 71 and enables said peak 67 to be turned from operative position to inoperative position.

When the peak 67 is moved in the direction indicated by the arrow 72, in Figure 1, the lug 66 will be permitted to move downwardly and the spring 34 will draw down the plate G. This will disengage the pawl 39 from the ratchet 40. At the same time, the lip 38 will press against the projection 61 and move the plate J so that the detent 60 is disengaged from the ratchet 40.

In operation, the coin M is inserted in the slot 14 and then is received between the swinging plate F and the reciprocating plate G.

The coin is held in position by means of the flanges 19 and 20 on the swinging plate. Then the plate is moved in the direction 43 from the position of Figure 5 to the position indicated in Figures 6-7.

Upon this movement, the coin will strike the flanges 42 and 44 respectively projecting from the wall 18 and the reciprocating plate G.

When the coin strikes the tang or inwardly turned portion 42, as indicated in Figure 6, continued propulsion of the coin by the flange 19 will cause the coin to elevate the flange 44 to the position shown in Figure 7. This will elevate the plate G from the position of Figure 6 to the position of Figure 7 extending the spring 34.

The movement of the swinging plate F will be limited by contact between said plate and the flange 42, as indicated in Figure 7, said flange 42 contacting the inside edge 42a of the recess 42b, in the swinging plate F.

At the extreme position of the plate F, as shown in Figure 7, the coin M will be projected into the casing of the tank A.

During this upward movement of the plate G, the pawl 39 will have moved the ratchet 40 one tooth resulting in the designating strip N being moved from the roller H to the roller I by one position and exposing a different indication through the window 12.

The detent 60 will prevent any reverse movement of the pawl 40 and at the same time will

hold the pawl in position during the successive movements of the reciprocating plate G. As soon as the coin is released, the plate G will be returned to its prior position by the spring 34 with the flange 66 at its lower edge abutting the peak 67 of the contact member K, as shown in Figures 1 and 3.

At the same time, the spring 23 will return the swinging plate F to its initial position as shown in Figures 2 and 5 from the ejecting position shown in Figures 6 and 7.

Ordinarily, the strip N is of sufficient length so that it will record the contents of the bank until the bank is completely filled.

When the bank is returned to the institution to be opened, the bottom 10 may be removed by an operating latching device such as shown in my copending application, Serial No. 241,568, filed November 21, 1938, and the contents of the bank may then be removed.

At the same time, the indicator strip N may be returned to zero position. This is accomplished by reaching up through the casing 11 and swinging the plate K in the direction 72 by the handle portion 70.

When this plate is moved in the direction indicated by the arrow 72, in Figure 1, the spring 34 will draw down the reciprocating plate G removing the pawl 39 from the ratchet 40.

At the same time, the lug 38 will strike the projection 61 on the plate J (see Figures 2 and 8) and the strength of the spring 34 will be such that the detent 60 will be moved away from the ratchet 40. Then the rollers H and I may be moved by the turning knob or key 100 so as to turn the indicator strip N to zero position.

As soon as this adjustment has been made the plate K will be turned back to the position shown in Figures 1 and 3, the plate G will be elevated and the spring 62 will cause the plate member J to move so that the detent 60 again engages the ratchet 40.

It is thus apparent that there is provided a simple, compact, durable and inexpensive registering mechanism particularly designed for small banks but also having many other applications.

The strip N may carry a calendar as well as other indicia and it may be used in any particular connection where a device is to be operated by a coin.

The device is very compact and only requires a small space inside the bank and it is very possible to get large, clear type upon the indicator strip N. The device cannot be readily tampered with and it may be readily reset.

A particular advantage of the present invention resides in the fact that the device is devoid of gearing enabling a more useful and simpler construction which may record any number of days or months or years or coins without being limited by the ratio or arrangement of the gearing.

The capacity of the device may be readily changed by changing the size of the rollers or drums H and I and the number of teeth upon the ratchet 40 may be considerably varied.

Regardless of the number of teeth on the ratchet 40, the strip may be continuously fed

from the upper drum H to the lower drum I and the number of teeth on the ratchet 40 need not correspond to the number of days, months, years or coins, as the case may be.

5 The key shown in Figure 10b and in utilization in Figures 10 and 10a may be utilized for opening the bottom of the bank as shown in the manner described in the copending application, in which case the recess 100b will cooperate with the bottom plate of the bank or it may be utilized as

10 indicated to reset the device back to zero by means of the slot 100c, shown in Figure 2, the end portion 100d of the key of Figure 10 fitting into said slot 100c.

15 It will be noted that it is not possible to reset the registering mechanism without the key of Figure 10b and that the key of Figure 10b, nevertheless, is of relatively simple construction.

Moreover, the drums when reset by the key of 20 Figure 10b can only be reset in a reverse direction to the feed of the strip N, said reverse direction being indicated in Figure 2 by the dotted arrow 100e.

It is apparent that the specific illustrations 25 shown above have been given by way of illustration and not by way of limitation and that the structures above described are subject to wide variation and modification without departing from the scope or intent of the invention, all of which variations and modifications are to be included within the scope of the present invention.

What is claimed is:

1. In a coin actuated registering device, a box 35 like structure having a coin receiving slot in one wall and a coin ejecting slot in an adjacent wall, said slots lying in the same plane, two plates positioned closely adjacent to still another wall which last mentioned wall is parallel to the plane 40 of the slots, said plates being spaced sufficiently apart to receive a coin between them, the space between them extending from the coin receiving slot to the coin ejecting slot, one plate being pivotally mounted on a wall of said box and having outstanding lugs to receive a coin from said receiving slot and to carry it to said ejecting slot upon movement of the plate from adjacent the first slot to adjacent the second slot and the other plate being mounted for reciprocatory movement 50 and having a lug actuated by the coin carried by the pivotally mounted plate.

2. The device of claim 1 in which said structure includes a registering ratchet and said reciprocatory plate carries means to actuate said ratchet.

3. The device of claim 1, said reciprocatory plate being provided with a spring biasing it away from said coin receiving slot, and means to releasably stop and limit the movement of said reciprocatory plate by said spring.

60 4. The device of the claim 1 in which said structure is provided with a registering ratchet and said reciprocatory plate carries an actuating pawl for said ratchet, said structure also including a fixed pawl for said ratchet, and means to release said actuating pawl and said fixed pawl to enable resetting of said ratchet.

EDWIN KLAHN.
